UNITED STATES PATENT OFFICE.

SALVATORE VIVIANO, OF ST. LOUIS, MISSOURI.

APPARATUS FOR DRYING MACARONI, SPAGHETTI, AND SIMILAR FOODS.

1,270,900.

Specification of Letters Patent.

Patented July 2, 1918.

Application filed August 22, 1917. Serial No. 187,614.

To all whom it may concern:

Be it known that I, SALVATORE VIVIANO, a citizen of the United States, residing at St. Louis, Missouri, have invented a certain new and useful Improvement in Apparatus for Drying Macaroni, Spaghetti, and Similar Foods, of which the following is a full, clear, and exact description, such as will enable others skilled in the art to which it appertains to make and use the same.

This invention relates to an apparatus for drying macaroni, spaghetti and other foods of a similar nature. In the manufacture of foods of the character mentioned it is now the general practice to remove the macaroni or spaghetti from the machine in which it is formed and loop it over long sticks or bars which are then carried into a heated drying room and placed on racks. This drying room, which is maintained at a very high temperature, is equipped with fans arranged in such a manner that blasts of hot air will be blown downwardly onto the macaroni suspended from the sticks on the racks, it being the usual practice to leave the macaroni in said heated drying room for a period of from two to three hours, so as to completely dry the outer surface of the macaroni. Thereafter, the sticks containing the macaroni are carried into another room or compartment wherein the macaroni is subjected to a "sweating" process which causes the moisture on the inner side of the macaroni to be drawn outwardly to the outer surface of the macaroni. After being subjected to this sweating process for a period of from ten to twelve hours the sticks containing the macaroni are carried into a room and placed on racks where they are left for a period of about eight days, or until the macaroni has become completely dried by exposure to air at atmospheric temperature. The sticks containing the macaroni are carried manually by workmen from the machine in which the macaroni is formed into the heated drying room, then from the heated drying room into the sweating room and then into the room in which the air drying process is carried on. Consequently, there is a great deal of waste, due to the breakage that naturally results from frequently handling the macaroni, and moreover, such a method of drying macaroni tends to produce a product that is not absolutely clean, as it is impossible, even where the greatest care is exercised, to prevent all dirt and dust from lodging on the

macaroni when it is handled so many times and carried into three different rooms. The excessive heat to which the macaroni is subjected in the heated drying room tends to bleach or destroy the natural color of the macaroni and also tends to make the macaroni curl up, both of which features are undesirable from a commercial standpoint. Moreover, such a method of drying macaroni is slow and costly, as it usually requires about nine days to completely dry the macaroni and necessitates the employment of a large number of operatives to carry the macaroni from one room to another. The excessive heat to which the workmen are subjected when carrying the macaroni into and out of the heated drying room is also a very objectionable feature of the method now in-general use.

The main object of my invention is to provide an apparatus for drying macaroni, spaghetti and similar foods that reduces waste, that insures a clean product, and which will dry macaroni quickly without causing it to bleach or curl up.

To this end I have devised an apparatus that comprises a rack or similar device arranged in a room and adapted to receive the macaroni after it is removed from the machine in which it is formed, and means of novel construction for causing air to flow longitudinally through said room in one direction and be distributed uniformly over the macaroni for a certain period and then longitudinally through the room in the opposite direction, the direction of travel of the air being reversed intermittently until the drying operation is completed.

The complete drying operation is performed in the room in which the macaroni was taken after being removed from the machine in which it was formed and during the entire drying operation the macaroni is not handled or removed from the racks on which it was first placed. Consequently, there is very little waste in my method due to breakage of the macaroni and the product is clean. Moreover, my apparatus makes it possible to completely dry the macaroni in a period varying from three to four days, depending upon atmospheric conditions.

Figure 1 of the drawings is a vertical sectional view of my improved apparatus; and

Fig. 2 is a vertical cross-sectional view, taken on the line 2—2 of Fig. 1.

Referring to the drawings, A designates

a room or compartment of any preferred shape and size, provided at its opposite ends with openings, not shown, and which is equipped with racks B on which sticks or rods C containing macaroni α can be arranged, the macaroni being looped over the sticks C so that it hangs downwardly from same in double strands, as shown in Fig. 2. Said room or compartment can be formed 5 from any suitable material and in various ways without departing from the spirit of my invention, so long as it is of such a character that it will form a passageway through which air can flow longitudinally first in one 10 direction for a certain period and then in the opposite direction for a certain period. Means is provided for causing air, preferably at atmospheric temperature, to flow longitudinally through the room A over the 15 macaroni suspended from the sticks C, and while various means may be used for this purpose without departing from the spirit of my invention, I prefer to use one or more fans D arranged so that currents of air will 20 travel longitudinally of the room A in a direction parallel to the sticks C from which the macaroni is suspended, thereby causing the air to come in contact with both strands of each piece of macaroni. The fans D are 25 preferably so constructed that the air will be distributed equally and uniformly over all of the macaroni in the room A, thereby insuring even drying of the macaroni. In the apparatus herein shown the fans D are 30 provided with tapered blades 1 which are widest at their inner ends and gradually diminish in width toward their outer ends, as shown in Fig. 2. In other words, each of the fan D is provided with blades 1 which 35 are so proportioned that when the fan is in operation the volume of air expelled from or set in motion by the center of the fan will be substantially the same as the volume of air set in motion by the outer end portions 40 of the blades 1 of the fan.

In the apparatus herein shown two fans are employed which are arranged between three racks B, the blades of said fans being long enough so that air will be forced or 45 drawn uniformly over all of the macaroni on each of the racks B. It is immaterial, so far as my broad idea is concerned, how many fans are employed, but it is essential that the fans be arranged in such a manner that there 50 are no baffles between the fan and racks B, and further, that the fans be provided with tapered blades 1 of the form above described, as such an arrangement makes it possible to drive the fans at a comparatively slow speed 55 with a small electric motor and still obtain an even and equal distribution of air over all of the macaroni in the room A. One convenient way of operating the fans D is to connect up each fan with a countershaft 2 60 by means of a belt 3 and drive said counter-

shaft 2 by a belt 4 that passes over a pulley 5 on an electric motor 6. If desired, the apparatus can comprise means for raising the temperature of the room A so as to cause the macaroni to sweat at a certain stage or 70 at certain stages in the drying operation, the means herein shown for this purpose consisting of one or more radiators E or steam coils arranged in the room A, as shown in Fig. 1 and adapted to be heated by steam or 75 any other suitable heating medium. However, it is not essential to the successful operation of my method that the temperature of the room be increased during the drying operation, as the macaroni generally contains sufficient moisture to cause it to sweat. 80

In using my apparatus the macaroni, after being removed from the machine in which it is formed, is looped over the sticks C which are then carried into the room A and arranged horizontally on the racks B in said room. Thereafter, the fans D are started so as to cause air to flow longitudinally through the room A in one direction for a period of time that will vary according 90 to atmospheric conditions, but which is usually from one to two hours. Said fans are then reversed and operated for a period of from one to two hours, so as to cause air to flow longitudinally through the room A in 95 the opposite direction, so as to insure all portions of all of the macaroni in the room being acted upon by moving air, the air being at atmospheric temperature, unless atmospheric conditions necessitate or make 100 it desirable to heat the air slightly. A reversing motor can be used for operating the fans, or any other suitable means can be used for changing the direction of rotation of the fans. If the outer surface of the macaroni 105 becomes dry after the fans have been in operation for a short period, the fans can be stopped and the temperature of the room A raised by admitting steam or any other suitable heating medium to the radiators E, so 110 as to cause the macaroni to sweat, and thus draw the water on the inside of the macaroni outwardly to the outer surface of the macaroni. The supply of steam to the radiators is continued for a short period and is 115 then cut off. In most instances, however, the macaroni contains sufficient moisture to overcome the necessity of raising the temperature of the room so as to cause the macaroni to sweat. Thereafter, the fans D are started 120 and are operated intermittently at frequent intervals until the macaroni has become completely dried, the time usually required to completely dry the macaroni being from three to four days. 125

With such an apparatus there is very little waste due to breakage of the macaroni, owing to the fact that the macaroni is not handled after being placed on the racks B. Moreover, such an apparatus produces clean 130

- macaroni that is straight and of natural color, due to the fact that at no stage in the drying operation is the macaroni subjected to hot blasts of air, as in the method now generally used for drying macaroni. In addition to the desirable features above pointed out, my apparatus makes it possible to dry macaroni in about one-half of the time required by the method now generally used; it is inexpensive to build and it eliminates a number of operatives which heretofore were employed to carry the macaroni from one room to another during the operation of drying same.
- 15 While I have herein illustrated my apparatus as being used for drying long strips of macaroni, it will, of course, be understood that said apparatus can be used for drying "cut" macaroni or short pieces of macaroni contained in trays that are placed on the racks in the drying room.
- Having thus described my invention, what I claim, and desire to secure by Letters Patent, is:
- 25 1. An apparatus for drying macaroni and the like, comprising a room or compartment,
- a rack in said room on which the macaroni is placed, and a fan arranged in said room in close proximity to said rack with no baffle or similar obstruction between the fan and the rack, said fan being provided with blades which gradually diminish in width toward their outer ends, thereby insuring an equal and uniform distribution of air over all of the macaroni in the room when the fan is in operation.
2. An apparatus for drying macaroni and the like, comprising a room or compartment, two structures in said room that are adapted to contain macaroni or the like, and a fan arranged between said structures with no baffles or the like between said structures and fan and constructed in such a manner that when it is in operation air will flow longitudinally through said room and be distributed evenly and uniformly over the macaroni, said fan being adapted to be reversed so as to cause the air to flow longitudinally of the room in one direction for a certain period and then longitudinally of the room in the opposite direction for a certain period.

SALVATORE VIVIANO.
